UNITED STATES PATENT OFFICE.

ISAAC H. LEVIN, OF NEWARK, NEW JERSEY, ASSIGNOR TO INTERNATIONAL OXYGEN COMPANY, A CORPORATION OF NEW JERSEY.

ELECTROLYTIC APPARATUS

1,153,168.

Specification of Letters Patent. Patented Sept. 7, 1915.

Original application filed May 9, 1913, Serial No. 766,469. Divided and this application filed February 26, 1914. Serial No. 821,126.

To all whom it may concern:

Be it known that I, ISAAC H. LEVIN, a citizen of the United States, residing at Newark, in the county of Essex and State of New Jersey, have invented certain new and useful Improvements in Electrolytic Apparatus, of which the following is a specification, reference being had therein to the accompanying drawings, which form a part thereof, this application being a division 10 of my application filed May 9, 1913, Serial No. 766,469.

My invention relates to electrolytic apparatus and more particularly to a type of diaphragm apparatus especially adapted for use in the dissociation of oxygen and hydrogen entering into an electrolyte.

This invention relates more particularly to electrodes for use in such an apparatus, 20 and has for its object the production of such an electrode, or such an electrolytic couple for the purpose of increasing the efficiency of the apparatus, by so constructing and arranging the electrodes as to avoid 25 the destruction thereof through corrosion.

A further object is to so construct the electrodes as to minimize resistance to the electric current at the anode or cathode, thus increasing the effective decomposition 30 of the electrolyte with a current of low voltage, and avoiding the necessity for excess voltage over that required in decomposing the electrolyte.

The invention consists in the novel features of construction and combination of parts hereinafter set forth and described and more particularly pointed out in the claims thereto appended.

Referring to the drawings: Figure 1 is an 40 elevation of one of the electrodes showing a part of the diaphragm in relation thereto, and a portion of a reticulated screen interposed between the diaphragm and the plate of the electrode; Fig. 2 is a section on the line 2—2 of Fig. 1; Fig. 3 is a section on the line 3—3 of Fig. 1; Fig. 4 is a cross sectional view of two adjoining electrodes, a diaphragm being shown in place between said electrodes.

50 Like letters refer to like parts throughout the several views.

Electrodes made in accordance with my invention are adapted to be arranged in pairs to form a cell, the elements of each

cell being separated by an interposed gas 55 impervious diaphragm.

In the form of the invention shown in the drawings, each electrode comprises a frame *a* having secured thereto, or formed therewith, in a manner to prevent the passage of 60 the electrolyte therethrough, a metallic plate *b* so set within said frame as to cause said plate and the plate of an adjoining electrode to be spaced apart sufficiently to form a chamber or cell therebetween. The 65 frame *a* is provided with the projection *a'* at the top thereof, having a plurality of openings *c—d* communicating by means of the ducts *c'—d'* respectively, with opposite sides of the plate *b*. The lug or projection 70 *a'* extends beyond the perimeter or outer edge of the frame *a*, so that any leak from the openings *c—d* will be into atmosphere and hence readily detected. The openings 75 *c—d* are so arranged that they are adapted to register with similar openings in other frames *a* to form a continuous duct by means of which communication is established between that portion of each cell adjacent 80 the anode and that portion of each cell adjacent the cathode, or between opposite sides of the plate *b* to the offtake or storage mechanisms. About each opening *c—d*, the projection or lug *a'* has formed therein a seat *c"—d"* for a packing gasket as *c"—d"*. 85 The bottom of the frame *a* is provided with a plurality of openings *e—f* preferably arranged in a projection or lug *a"*, similar to the lug *a'*, said openings being in communication with opposite sides of the 90 plate *b* through the ducts *e"—f"*.

The openings *e—f* are adapted to register with similar openings in adjoining lugs *a"*, and to form therewith a continuous duct adapted to be in communication with separate 95 sources of supply of the electrolyte, so as to convey the electrolyte from said sources of supply respectively to adjacent the anode or adjacent the cathode of each cell. By this construction the space adjacent the 100 anode may be supplied from one source of supply while that adjacent the cathode may be supplied from another source of supply, thus preventing oxygen being delivered with the electrolyte adjacent the cathode and 105 hydrogen being delivered with the electrolyte adjacent the anode. That portion of the frame *a* adjacent each of the openings

- e-f* is provided with at least one counter-sunk gasket seat *e²-f²* for the gasket *e³-f³* which is used in forming a continuous watertight adjoining between the joint electrodes.
- 5 Seated between each frame *a* and the frame *a* of the adjoining electrode, is a diaphragm *g*, preferably composed of asbestos or any other suitable material permeable to the electrolyte, the edge of which diaphragm
- 10 seals the inner edge of the perimeter of said frames forming both a water and gas tight joint. If desired, packing other than the diaphragm may be used for the purpose of forming this joint.
- 15 To secure the maximum surface for the plates *b*, I use corrugated sheets of rolled or cast metal as shown, and the thickness of these plates relative to that of the frames *a* is such as to bring them as close together as
- 20 possible to reduce the internal resistance of each cell. The peaks of the corrugation will tend to prevent such distortion of the diaphragm *g* as would bring it in contact with the surface of the plate, but to insure against
- 25 any possibility of such distortion, I provide the surface of each plate with a plurality of projections *b'*. To insure the circulation of the electrolyte about all portions of the faces of each plate, I cut away each corrugation,
- 30 which cut away portions are indicated at *b²*, in a manner to permit the electrolyte to pass from one side of each corrugation to the other side thereof.

If desired, the entire face of each plate *b* on both sides thereof may have a reticulated screen, as a wire mesh extended over the same, which mesh is indicated at *b³* in the drawings. This mesh while increasing the efficiency of each cell may be dispensed with

40 if desired as the apparatus is highly efficient without the use of such.

In operating an electrolytic apparatus of the character herein described, it has been found that the voltage of the current used

45 must always be in excess of the theoretical resistance of the cell, this excess voltage being probably required because of surface resistance at the electrodes. While with electrodes of similar metal, high efficiency can

be secured, I have found that by using an 60 anode and a cathode of dissimilar metals, or having dissimilarly metallized surfaces, I can secure greater economy in the operation of the apparatus or higher capacity with a given voltage.

55 In actual practice, I have found that a nickel surface for the anode and an iron surface for the cathode produce the best results, and so far as experiments have been able to determine, an iron plate *b* having 60 one surface thereof electro-plated with nickel, is more efficient than a large plate *b* consisting of an iron sheet and a nickel sheet associated in the frame *a*. Hence I prefer to use a bi-polar electrode 65 wherein that portion forming the anode, indicated at *h* in the drawings, presents a nickel surface, and that portion forming the cathode indicated at *i* presents an iron surface.

70 It is not my intention to limit myself to the precise details of construction shown in the accompanying drawings, it being apparent that such may be varied without departing from the spirit and scope of the invention.

75 Having described my invention what I claim as new and desire to have protected by Letters Patent is:—

1. An electrolytic apparatus embodying 80 therein a bi-polar electrode, the anode of which has a nickel surface and the cathode of which has an iron surface.

2. An electrolytic apparatus embodying 85 therein an electrolytic couple consisting of an iron anode having an operative surface composed of nickel applied thereto by electro-decomposition, and a cathode having an operative surface of iron.

In witness whereof, I have hereunto af- 90 fixed my signature in the presence of two subscribing witnesses, this 20th day of February, 1914.

ISAAC H. LEVIN.
